UNITED STATES PATENT OFFICE.

JOHN J. RALEK, OF NEW YORK, N. Y., ASSIGNOR TO HENRY R. HUNTING, OF SPRINGFIELD, MASSACHUSETTS.

BOOKBINDER.

1,301,320.

Specification of Letters Patent. Patented Apr. 22, 1919.

Application filed February 26, 1918, Serial No. 219,219. Renewed March 14, 1919. Serial No. 282,734.

To all whom it may concern:

Be it known that I, JOHN J. RALEK, a subject of the Emperor of Austria, and a resident of the city of New York, borough of

5 Manhattan, in the county and State of New York, have invented a new and Improved Bookbinder, of which the following is a full, clear, and exact description.

This invention relates to book binders or 10 the like and has particular reference to temporary binders for newspapers, magazines or the like, and making bound books.

Among the objects of the invention is to provide improved facilities for binding or 15 holding periodicals, the several units being adapted to be attached or filed in the binder in an easy manner individually, and then when the volume or assemblage is completed it may be removed from the binder in bound 20 form so as to be so retained for use like an ordinary book or filed away as may be desired, leaving the binder ready for a subsequent operation.

Another object of the invention is to provide 25 a temporary binder or the like having facilities for removal therefrom of an assemblage or collection of newspapers, sheets, magazines or the like at any time irrespect- 30ive of the completeness of the assemblage, the arrangement being such that such assemblage may be removed and replaced if desired, but whether complete or not the units of the assemblage may always be handled as a single complete volume when detached 35 from the binder.

With the foregoing and other objects in view the invention consists in the arrangement and combination of parts hereinafter described and claimed, and while the invention 40 is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a perspective view of my improved binder lying open and with a book or like assemblage of periodical units therein.

Fig. 2 is a fragmentary perspective view 50 of the binder showing the position of the clips preliminary to the introduction of the pin bar.

Fig. 3 is a similar view showing the pin bar attached and ready for the application 55 of the periodical units or signatures.

Fig. 4 indicates the next successive step or with one of the cover sheets in place on the pins.

Fig. 5 is a vertical transverse section of 60 the complete binder with a book therein, the section being on the plane of one of the pivots.

Fig. 6 is a detail view of one of the pins showing its relation to the pin bar. 65

Fig. 7 is a perspective view of one of the pivoted clips; and

Fig. 8 is a detail perspective view of a book bound by my improved binding device. 70

Referring now more particularly to the drawings I show a binder comprising a pair of stiff boards 10 and 11 of any suitable size, material or construction having their inner or adjacent edges connected by a flexible back 12 of any suitable strong, tough and 75 durable material.

13 indicates an anchor bar. This anchor bar is secured on the inside of the back adjacent and parallel to the inner edge of the board 11. Any suitable means may be provided to make this attachment permanent and secure, the means indicated as including a series of rivets 14, or their equivalent, each having a head on its outer end and clenched or upset on its inner end over the pivot end 80 15 of a friction clip 16. These clips as shown best in detail in Fig. 7 are throughout their main portion U-shaped in cross section except that the end 15 thereof is flat and of a length and width substantially 85 equal to the width of the anchor bar upon the inner face of which it is centrally pivoted. Any suitable number of these clips may be employed, depending upon the length of the anchor bar and other conditions. As indicated in Fig. 2 they are 90 adapted to be turned with comparative freedom around the axes of the pivots 14 95

when the binder is laid out flat and with the boards 10 and 11 lying in substantially the same plane.

17 indicates what I term the pin bar 5 formed of wood or some other relatively cheap stiff material and which becomes a part of the permanent binder for the book and detachable from the temporary binder. The pin bar constitutes a carrier or holder 10 for a series of pins 18 of any suitable nature but each having a head 19 of very slight thickness. The pin is indicated as having a plurality of prongs the points of which are adapted to pass through the periodical units 15 or holes formed therein at proper distances apart, and the points may then be bent down flat as shown in Figs. 1 and 8.

The pin bar 17 with the desired number of pins 18 projecting therethrough is put 20 directly upon the anchor bar while the clips are turned open as in Fig. 2. The clips are then turned parallel to the bars as indicated by dotted arcs as in Fig. 2, the U-shaped body portions of the clips engaging friction- 25 ally upon the pin bar as shown in Fig. 3. The space between the sides of each clip is substantially equal to the cross section of the pin bar. With the clips turned into embracing position from opposite sides of the 30 longitudinal axis of the anchor bar the pin bar will be held from movement in any direction until the clips are released therefrom. These clips may be made of any suitable strong but relatively thin sheet metal or its 35 equivalent. The reader's attention is now called to the cover strips for the book, the first one being shown at 20, the same having a rib 21 attached thereto as by means of a hinge strip 22 or the like. The rib 21 is 40 provided with holes 23 through which the pins pass, bringing the hinge portion of the cover strip directly on top of the pin bar and clips holding the same. The magazines, 45 newspapers or other periodical units or signatures shown at 24 are then put upon the pins, each unit thereof being held temporarily by the bending down of the pins. When the next unit is to be put in place, however, if the work is being done day after 50 day, or week by week according to the nature of the periodical, the points of the pins are bent up for this purpose and then bent down again after the next unit is applied.

55 25 indicates the last cover strip having a rib 26 and hinge 27 of a nature corresponding to the first cover strip. When the volume or book is completed the final cover strip 25 is put upon the pins; the pins passing through holes 28 formed through 60 the rib 26 and the points are then bent down finally as shown in Fig. 1. With the device lying out flat as shown in Fig. 1 the operator may easily withdraw a portion of the clips by applying his thumb or finger nail or other

instrument to the notched portion 16' thereof, the book is then turned over so that the operator has access to the remaining clips which are in turn withdrawn from the pin bar leaving the book free to be lifted from the binding device so that the book may 70 be filed away or used as any other book, and the binding device will be left in the form shown in Fig. 2 ready for a subsequent binding operation. In this connection I wish to make several observations, first, this device constitutes a means or device for binding books in succession rather than constituting a permanent binder for a book. In other words a book bound by this device is shown in Fig. 8, while the same binder as 80 a mechanical contrivance may be used repeatedly and indefinitely for binding purposes. Again, the pin bar may be furnished at a trifling cost, and but for the cover strips 85 20 and 25 the expense incident to the binding of each volume is exceedingly slight, covering only the pin bar, a few pins, a final bar similar to the pin bar and which takes the place of the rib 26 if the cover strips are not used. From what has just been stated it 90 is to be understood that for some purposes the cover strips 20 and 25 may not be required, in which case I employ simply the pin bar, a series of pins and a final bar that may be a duplicate of the pin bar. Obviously, however, a more serviceable book is formed with the use of the cover strips. 95

It will thus be seen that I provide a means or device for the easy and ready transfer of loose leaves or sheets from ledgers or 100 other temporary records and so bind them that they may be filed away for safe keeping and ready reference, and at a very trifling cost.

I claim:

1. The herein described binding device for repeated use in binding books, the same comprising in combination a flexible back, a relatively stiff anchor member fixed along one edge of the back, and a plurality of movable devices carried by said anchor member for detachable connection with one element of the permanent binder for the book being bound therein.

2. In a device for permanently binding 115 a book, the combination of a flexible back, a bar constituting an anchor member fixed to said back parallel to one edge thereof, and a plurality of clips pivoted to said anchor member, each clip comprising a body 120 of U-shape in cross section, substantially as set forth.

3. In a book binding device, the combination of a relatively rigid bar constituting an anchor member, means to hold said anchor member, and a series of clips pivotally connected for coöperation with one face of said anchor member, each clip comprising a body 125

of U-shape in cross section and a flat extension at one end thereof through which the fastening means therefor passes.

4. In a book binder, the combination with a plurality of units or signatures, cover strips embracing the same, a series of bendable holding devices passing through said

cover strips and signatures, and a carrier for said holding devices extending along and parallel to one of said cover strips, said carrier constituting a means for temporarily holding the book during the binding operation. 10

JOHN J. RALEK.
